EX

No. 13,635

February 20, 1883

UNITED STATES PATENT OFFICE.

JOHN PIRKL, OF BROOKLYN, NEW YORK.

DESIGN FOR A GATE.

SPECIFICATION forming part of Design No. 13,635, dated February 20, 1883.

Application filed December 21, 1882. Term of patent 7 years.

To all whom it may concern:

Be it known that I, JOHN PIRKL, of Brooklyn, in the county of Kings and State of New York, have originated and invented a new and useful Design for Ornamental Gates and Window-Guards; and I do hereby declare that the following is a full, clear, and exact description thereof, reference being had to the accompanying photograph, forming a part of this specification.

The present invention has relation to certain improvements in the design of ornamental gates and window-guards; and it consists substantially of the ornamental form and configuration illustrated in the accompanying photograph, and hereinafter described and claimed.

The photograph forming a part of this specification represents a front elevation of a gate or window-guard, which consists of an outer metal frame, A, inclosing the ornamental portion of the device, consisting of the following features: A series of wires, a, are bent to form elongated loops B, which are serpentine a portion of their length, as shown at b. These loops are arranged in two vertical rows, and terminate at their outer ends in circles C, and at their inner ends in circles D, upon each side of which are rosettes E. The rings or circles C D and the rosettes E, as well as the loops B, are arranged in vertical rows, and the serpentine portions b of the loops come together, which make a very neat and ornamental effect, as does the double line of rosettes and single line of the circles D. The circles C may have at the outer end a second circle or section of loops, as desired, this not being material in

effecting the ornamental configuration of the design.

Having now fully described my invention, 40 what I claim as new, and desire to secure by Letters Patent, is—

1. A design for gates or window-guards, consisting of an outer frame inclosing two vertical rows of loops, a central row of circles, and 45 a double row of rosettes arranged upon each side of the row of circles, substantially as shown and set forth.

2. A design for gates or window-guards, consisting of a double row of loops, bent in serpentine form a portion of their length, and terminating at their inner and outer ends in circles, substantially as shown and set forth.

3. A design for gates or window-guards, consisting of two rows of elongated loops, terminating at their inner and outer ends in circles, and a double row of rosettes arranged upon each side of the central row of circles, substantially as shown and specified.

4. A design for gates or window-guards, an 60 outer frame inclosing two vertical rows of elongated loops, which are serpentine a portion of their length and terminating at their inner and outer ends in circles, the central row of circles having arranged upon each side a row of rosettes, substantially as shown and described.

In testimony that I claim the foregoing as my own I affix my signature in presence of two witnesses.

JOHN PIRKL.

Witnesses:

JACOB F. HEALEY,
T. J. HEDGES.
